CLAIM

The ornamental design for a transparent monument, as shown and described.

DESCRIPTION

FIG. 1 is perspective view of a transparent monument incorporating the ornamental features of my design;

FIG. 2 is a top view thereof;

FIG. 3 is a front view thereof;

FIG. 4 is a side view thereof; and,

FIG. 5 is a rear view thereof.

The printing shown in broken lines in FIGS. 1, 3 and 5 is for illustrative purposes only and does not form part of the claimed design.

FIG.1.

FIG.2.

FIG.3.

FIG.4.

FIG.5.
